UNITED STATES PATENT OFFICE

CHARLES H. BURTON, OF WASHINGTON, DISTRICT OF COLUMBIA, ASSIGNOR OF ONE-HALF TO CHARLES W. FISHER, OF NEW YORK, N. Y.

PNEUMATIC-DISPATCH SYSTEM

Application filed June 16, 1930. Serial No. 461,468.

This invention relates to improvements in pneumatic dispatch systems, and more especially to a novel terminal for such systems.

The primary object of the invention is to provide a pneumatic dispatch terminal so constructed that when a shuttle or carrier arrives in the terminal, it will operate certain instrumentalities which will effect the movement of a plural cylinder carriage, so that the cylinder containing the carrier or shuttle will be transferred to a discharge station, while another cylinder will be brought into position to receive the next carrier or shuttle.

Another object is to furnish a terminal of this character, in which the cylinder carriage may be shifted without affecting pressure conditions existing in the main trunk through which the carrier or shuttle travels.

A still further object is to provide a terminal of this kind, in which the cylinder carriage is automatically reciprocated, so as to alternately bring each cylinder first into alignment with the main trunk, and then into alignment with a discharge station, and so on.

Another object is to so construct the terminal that the carriers or shuttles arriving therein automatically operate the control valves of a pressure fluid system which is employed to shift the carriage back and forth.

Another object is to furnish a terminal of this kind, in which the shifting of the carriage automatically opens pressure fluid control valves which admit a pressure fluid to the cylinders for blowing the shuttle or carrier out of the same on to an unloading platform or trough.

A further object is to provide a terminal having novel means for checking the impact when the shuttle arrives in the terminal, and for preventing the shuttle, due to the rebound, from passing again into the main air trunk.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is a side elevation of the improved terminal.

Fig. 2 is a top plan view of the same.

Fig. 3 is a horizontal sectional view partly in top plan, of the carriage shifting cylinder, 55 and its control valve means.

Fig. 4 is a vertical sectional view of one of the control valves, taken on the line 4—4 of Fig. 5.

Fig. 5 is a rear elevation of the trigger operated valves of the device.

Fig. 6 is a vertical transverse sectional view on the line 6—6 of Fig. 1, and with certain parts omitted.

Fig. 7 is a longitudinal vertical sectional view of a detail on the line 7—7 of Fig. 2.

In the drawings, 10 designates a tube, one end of which is to be connected to the terminal end of a pneumatic dispatch trunk, (not shown), the other end of the tube being joined by an air-tight joint, to the cheek plate 11 of a carriage support that is mounted on legs 12. The other cheek plate 13 of this support is connected to the first mentioned cheek plate by tie-rods 14, which tie-rods are omitted in Fig. 2 to facilitate illustration.

The cheek plate 11 has a centrally disposed aperture indicated by dotted lines as at 15, while the cheek plate 13 has two such apertures 16 at its end portions.

Horizontal grooves 17 at the upper ends of the legs form transverse tracks for V-shaped guides 18 of a cylinder carriage, which consists of apertured end plates 19 that are connected together by cylinders 20, and snugly engage cheek plates 11 and 13.

From Fig. 2 it will be observed that one of the carriage cylinders is in alignment with the tube 10, so that a shuttle from the main trunk will pass through the tube into this cylinder. When the carriage is in this position, the other cylinder is in alignment with one of the apertures 16, whereby a shuttle in the last mentioned cylinder may be ejected on to an unloading trough or station 21, which is secured to the cheek plate 13.

When the carriage is shifted transversely, one of the cylinders 2 will be moved to one side to bring the same into position to discharge its shuttle on to an unloading trough.

or station 22, while the other cylinder is brought into alignment with the tube 10. The unloading troughs may be partially supported by legs 23.

5 For the purpose of automatically reciprocating the carriage, one of the cylinders is provided with a depending arm 24 which is rigidly connected to the outer end of a piston rod 25. The inner end of this rod is 10 rigidly connected to a piston 26 which reciprocates in a transversely arranged cylinder 27, that is located between the cylinders, and is anchored by any suitable means, not shown, to the stationary frame or support.

15 A pressure fluid, such as compressed air, is alternately admitted to, and discharged from the opposite ends of the cylinder 27, through pipes 28 and 29, which are connected at the 20 point 30 to a conduit 31 which admits the pressure fluid to this portion of the system.

25 A common control valve 32 of the reciprocating type is interposed in the pipes 28 and 29, and this valve has a pair of inlet ports 33 and 34, and a pair of exhaust grooves 35 and 36.

30 From Fig. 3 it may be seen that the pressure fluid is travelling into one end of the cylinder through the port 33, for the purpose of forcing the piston in one direction, and thereby shifting the carriage, and at the same time, the fluid from the opposite side of the piston is exhausting through the groove 36.

35 The valve 32 is shifted by means of a control piston 37 which reciprocates in a control cylinder 38. Opposite ends of the cylinder 38 are connected by pipes 39 and 40 to a conduit 41 which is joined to the pipe 29, so that 40 the pressure air is constantly supplied to the conduit 41.

45 Reciprocating valves 42 and 43 are interposed respectively in the pipes 39 and 40, and as best shown in Figs. 4 and 5, the active members 44 and 45 of these valves are each provided with an inlet port 46 and an exhaust groove 47. Obviously, when the inlet port of one of these valves is in alignment with its pipe, the pressure fluid will travel 50 to one end of the control cylinder 38.

55 For the purpose of causing one of the valves 42, 43 to exhaust while the other is admitting pressure fluid to the control cylinder, the active members of these valves are joined to opposite ends of a walking beam 48, which is pivotally supported at 49 by a bridge 50 which joins the two valve casings.

60 The upper ends of the active members 44 and 45 are pivotally connected to the rear 65 ends of trigger actuated levers 51 and 52, and each of these levers has its medial portion pivotally mounted at 53 on the cheek plate 13 of the support. These levers are positioned slightly to opposite sides of the 70 vertical center of the cheek plate, and their

free ends project forwardly as shown in Figs. 1 and 2.

70 These free ends are operated by means of fingers 54 and 55 which project upwardly from triggers 56 and 57 that extend into the cylinders 20. Consequently, when a shuttle arrives in one of the cylinders and operates the trigger of the latter, the pin of that trigger will force the front end of one of the levers (51, 52), upwardly, so as to depress the active member (44, 45) of the corresponding valve, whereby that valve will admit air to the control cylinder 38. Of course, as that active member descends, the walking beam 48 will raise the active member of the opposite valve, and the last mentioned active member will cause the other rocking lever (51, 52) to swing so that its forward end will descend, to be in the path of movement of the trigger finger of the next cylinder, 85 when the carriage is shifted.

80 One of the shuttles or carriers is shown at 57 in Fig. 7, and it will be noted that it has guide wheels or castors 58 at one end, as well as a central projection 59. When 90 the shuttle comes into the terminal, the projection 59 strikes the head 60 of a bumper, which head is backed by a coil spring 61, housed in a casing 62 that is arranged on the rear face of the central portion of the cheek 95 plate 13. This device will take up the impact caused by the shuttle being driven by air pressure into the terminal, and as the shuttle will rebound, due to the spring 61, each cylinder 20 is provided with a spring-pressed 100 catch 63 to prevent the shuttle from rebounding out of the terminal cylinder.

105 The pressure fluid supply is also joined by pipes 64 and 65 to the side portions of the front cheek plate 11, and this plate has 110 a pair of valves 66 and 67 to control the passage of the air into either one of the cylinders 20, when the latter is in alignment with its discharge trough 21, 22. The active members 68, of the valves 66 and 67 are normally held in closed position by springs 69, and the outer end of each active member is hooked over as shown at 70, so as to be in the path of movement of the carriage. Consequently, as the carriage reciprocates, it 115 will open the valves 66, 67 at the proper times to allow pressure air to force the shuttle from either of the cylinders 20, through one of the apertures 16 on to the unloading trough.

120 In operation, it will be assumed that the parts are in the positions shown in the drawings, at which time one of the cylinders 20 is in position to receive a shuttle 57 from the tube 10. As the shuttle enters the last mentioned cylinder 20, it strikes the trigger of that cylinder, and consequently, raises the forward end of the lever 51, with the result that the active member of the valve 43 is depressed to bring its inlet port 46 in align- 130

ment with the pipe 40. Consequently, air will be admitted to the control cylinder 38 to shift the valve 32, and thereby bring the port 33 into alignment with the pipe 38, with the result that air will be admitted to the cylinder 27 to cause the piston 26 to shift the cylinder carriage in a direction away from the cylinder 27.

As the carriage is shifted to bring one of the cylinders in alignment with the trough 22, the carriage will strike the hooked end 70 of the air valve 67, and air will enter the last mentioned cylinder to drive the shuttle on to the unloading trough 22.

At the same time, the other cylinder 20 is brought into such position that its trigger pin 55 comes beneath the forward end of the lever 52, and then when the next shuttle arrives, the trigger pin 55 will be raised, so as to elevate the forward end of the lever 52 and depress the active member of the valve 42, whereby air will travel through the line 39 into the opposite end of the control cylinder 38, to shift the valve 32 and bring the port 34 in alignment with the pipe 29, whereby air will enter the opposite end of the cylinder 27 and return the piston to its former position.

From the foregoing it is believed that the construction, operation and advantages of the invention may be readily understood, and it is apparent that changes may be made in the details disclosed, without departing from the spirit of the invention, as expressed in the claims.

What is claimed and desired to be secured by Letters Patent is:

1. A pneumatic dispatch terminal comprising a terminal trunk tube, unloading stations arranged out of alignment with the axis of said tube, a movable carriage provided with open-ended cylinders, each one of which is to be brought first into alignment with the tube and then into alignment with one of the unloading stations, a shuttle adapted to pass from the tube into any one of the cylinders, and means controlled by the shuttle for shifting said carriage.

2. A pneumatic dispatch terminal comprising a terminal trunk tube, a pair of unloading stations arranged at opposite sides of the axis of said tube, a movable carriage provided with open-ended cylinders, each one of which is to be brought first into alignment with the tube and then into alignment with one of the unloading stations, a shuttle adapted to pass from the tube into any one of the cylinders, means controlled by the shuttle for shifting said carriage, said carriage being provided with guides extending transversely of the tube and unloading stations, and tracks for said guides.

3. A pneumatic dispatch terminal comprising a terminal trunk tube, a pair of unloading stations arranged at opposite sides

of the axis of said tube, a movable carriage provided with open-ended cylinders, each one of which is to be brought first into alignment with the tube and then into alignment with one of the unloading stations, a shuttle adapted to pass from the tube into any one of the cylinders, means controlled by the shuttle for shifting said carriage, said carriage comprising apertured cheek plates provided with guides, the ends of the cylinders registering with the apertures of the cheek plates, and tracks for said guides extending transversely of the tube and unloading stations.

4. A pneumatic dispatch terminal comprising a terminal trunk tube, a pair of unloading stations arranged at opposite sides of the axis of said tube, a movable carriage provided with open-ended cylinders, each one of which is to be brought first into alignment with the tube and then into alignment with one of the unloading stations, a shuttle adapted to pass from the tube into any one of the cylinders, and means controlled by the shuttle for shifting said carriage, the control means for shifting the carriage comprising triggers extending into the cylinders.

5. A pneumatic dispatch terminal comprising a terminal trunk tube, a pair of unloading stations arranged at opposite sides of the axis of said tube, a movable carriage provided with open-ended cylinders, each one of which is to be brought first into alignment with the tube and then into alignment with one of the unloading stations, a shuttle adopted to pass from the tube into any one of the cylinders, means controlled by the shuttle for shifting said carriage, and means for absorbing the shock when the shuttle passes into one of the cylinders while it is in alignment with said tube.

6. A pneumatic dispatch terminal comprising a terminal trunk tube, a pair of unloading stations arranged at opposite sides of the axis of said tube, a movable carriage provided with open-ended cylinders, each one of which is to be brought first into alignment with the tube and then into alignment with one of the unloading stations, a shuttle adapted to pass from the tube into any one of the cylinders, and means controlled by the shuttle for shifting said carriage, each cylinder being provided with a rebound check to prevent the shuttle after it arrives in the cylinder from rebounding back into said tube.

7. A pneumatic dispatch terminal comprising a trunk terminal tube, unloading stations spaced endwise away from an end of the tube and positioned at opposite sides of the axis of the latter, a cheek plate fixed to the last mentioned end of the tube and having an aperture in its medial portion, a shuttle adapted to travel through said tube and to be discharged through said aperture, said cheek plate projecting laterally at opposite sides

of the tube, a pressure fluid supply port in each end portion of the cheek plate, each port being in substantial alignment with one of the unloading stations, valves controlling said ports, a shiftable carriage arranged between the cheek plate and the unloading stations and provided with a plurality of cylinders into any one of which the shuttle may pass from said tube, means for shifting the carriage, the carriage controlling said valves whereby air admitted to either one of the cylinders when the latter is in alignment with its unloading station will cause the shuttle to be discharged from the cylinder on to its unloading station.

8. A pneumatic dispatch terminal including a trunk discharge tube, unloading stations spaced endwise from the tube and arranged at opposite sides of the axis of the latter, stationary cheek plates arranged in spaced relation, one of said cheek plates being secured to the discharge end of the tube and having a centrally disposed aperture, the other cheek plate being connected to the forward ends of the unloading stations and having end apertures in alignment with said stations, a reciprocating carriage provided with apertured cheek plates and cylinders, the apertures of the last mentioned cheek plates aligning with the ends of the cylinders, the carriage cheek plates snugly engaging the stationary cheek plates to prevent the escape of air from any one of the cylinders when the latter is aligned with the tube, a shuttle adapted to travel through the tube into any one of the cylinders when the latter is aligned with the tube, and means controlled by the movement of the shuttle for reciprocating said carriage, whereby a cylinder, after receiving the shuttle, is shifted out of alignment with the tube and into alignment with one of the unloading stations.

9. A pneumatic dispatch terminal including a trunk discharge tube, unloading stations spaced endwise from the tube and arranged at opposite sides of the axis of the latter, stationary cheek plates arranged in spaced relation, one of said cheek plates being secured to the discharge end of the tube and having a centrally disposed aperture, the other cheek plate being connected to the forward ends of the unloading stations and having end apertures in alignment with said stations, a reciprocating carriage provided with apertured cheek plates and cylinders, the apertures of the last mentioned cheek plates aligning with the ends of the cylinders, the carriage cheek plates snugly engaging the stationary cheek plates to prevent the escape of air from any one of the cylinders when the latter is aligned with the tube, a shuttle adapted to travel through the tube into any one of the cylinders when the latter is aligned with the tube, and means controlled by the movement of the shuttle for

reciprocating said carriage, whereby a cylinder, after receiving the shuttle, is shifted out of alignment with the tube and into alignment with one of the unloading stations, the last mentioned means including trigger actuated pins projecting from the cylinders, and valve controlled levers actuated by the pins and supported by one of the stationary cheek plates.

10. A pneumatic dispatch terminal including a trunk discharge tube, unloading stations spaced endwise from the tube and arranged at opposite sides of the axis of the latter, stationary cheek plates arranged in spaced relation, one of said cheek plates being secured to the discharge end of the tube and having a centrally disposed aperture, the other cheek plate being connected to the forward ends of the unloading stations and having end apertures in alignment with said stations, a reciprocating carriage provided with apertured cheek plates and cylinders, the apertures of the last mentioned cheek plates aligning with the ends of the cylinders, the carriage cheek plates snugly engaging the stationary cheek plates to prevent the escape of air from any one of the cylinders when the latter is aligned with the tube, a shuttle adapted to travel through the tube into any one of the cylinders when the latter is aligned with the tube, and means controlled by the movement of the shuttle for reciprocating said carriage, whereby a cylinder, after receiving the shuttle, is shifted out of alignment with the tube and into alignment with one of the unloading stations, the last mentioned means including a pair of valves, each valve having an active member, means connecting said active members to cause one of the same to open its respective valve when the other one is closed, a pair of levers pivotally connected to said active members, and trigger actuated elements projecting from the cylinders and arranged to actuate the last mentioned levers.

11. A pneumatic dispatch terminal including a trunk discharge tube, unloading stations spaced endwise from the tube and arranged at opposite sides of the axis of the latter, stationary cheek plates arranged in spaced relation, one of said cheek plates being secured to the discharge end of the tube and having a centrally disposed aperture, the other cheek plate being connected to the forward ends of the unloading stations and having end apertures in alignment with said stations, a reciprocating carriage provided with apertured cheek plates and cylinders, the apertures of the last mentioned cheek plates aligning with the ends of the cylinders, the carriage cheek plates snugly engaging the stationary cheek plates to prevent the escape of air from any one of the cylinders when the latter is aligned with the tube, a shuttle adapted to travel through the tube

into any one of the cylinders when the latter is aligned with the tube, and means controlled by the movement of the shuttle for reciprocating said carriage, whereby a cylinder, after receiving the shuttle, is shifted out of alignment with the tube and into alignment with one of the unloading stations, the last mentioned means comprising a stationary cylinder, a piston reciprocating in the last mentioned cylinder, and operatively connected with said carriage, means for admitting a pressure fluid to opposite ends of said stationary cylinder, and means for controlling the admission and discharge of fluid to and from the opposite ends of the stationary cylinder.

12. A pneumatic dispatch terminal including a trunk discharge tube, unloading stations spaced endwise from the tube and arranged at opposite sides of the axis of the latter, stationary cheek plates arranged in spaced relation, one of said cheek plates being secured to the discharge end of the tube and having a centrally disposed aperture, the other cheek plate being connected to the forward ends of the unloading stations and having end apertures in alignment with said stations, a reciprocating carriage provided with apertured cheek plates and cylinders, the apertures of the last mentioned cheek plates aligning with the ends of the cylinders, the carriage cheek plates snugly engaging the stationary cheek plates to prevent the escape of air from any one of the cylinders when the latter is aligned with the tube, a shuttle adapted to travel through the tube into any one of the cylinders when the latter is aligned with the tube, and means controlled by the movement of the shuttle for reciprocating said carriage, whereby a cylinder, after receiving the shuttle, is shifted out of alignment with the tube and into alignment with one of the unloading stations, the last mentioned means including triggers arranged in the cylinders, elements actuated by the triggers and projecting from the exterior of the cylinders, rocking levers actuated by said elements, valves actuated by said levers, an air cylinder, a piston in the last mentioned cylinder operatively connected to the carriage, and means controlled by said valves for admitting air to and discharging air from the opposite ends of the air cylinder.

13. A pneumatic dispatch terminal including a trunk discharge tube, unloading stations spaced endwise from the tube and arranged at opposite sides of the axis of the latter, stationary cheek plates arranged in spaced relation, one of said cheek plates being secured to the discharge end of the tube and having a centrally disposed aperture, the other cheek plate being connected to the forward ends of the unloading stations and having end apertures in alignment with said stations, a reciprocating carriage provided with apertured cheek plates and cylinders, the apertures of

the last mentioned cheek plates aligning with the ends of the cylinders, the carriage cheek plates snugly engaging the stationary cheek plates to prevent the escape of air from any one of the cylinders when the latter is aligned with the tube, a shuttle adapted to travel through the tube into any one of the cylinders when the latter is aligned with the tube, and means controlled by the movement of the shuttle for reciprocating said carriage, whereby a cylinder, after receiving the shuttle, is shifted out of alignment with the tube and into alignment with one of the unloading stations, the last mentioned means comprising a stationary air cylinder, a reciprocating piston arranged in said cylinder and operatively connected to the carriage, pipes connected to the opposite ends of the air cylinder, means for admitting pressure air into said pipes, a control valve for controlling the passage of air through said pipes, and trigger controlled means for shifting said valve.

In testimony whereof I affix my signature.
